UNITED STATES PATENT OFFICE.

JOIN BEST, OF PATERSON, NEW JERSEY.

DESIGN FOR A BADGE.

SPECIFICATION forming part of Design No. 21,859, dated September 13, 1892.

Application filed July 22, 1892. Serial No. 440,960. Term of patent 3½ years.

To all whom it may concern:

Be it known that I, JOHN BEST, a citizen of the United States, residing at Paterson, county of Passaic and State of New Jersey, have invented and produced a new and original Design for Woven Silk Badges, of which the following is a specification, reference being had to the accompanying photographic print, forming a part thereof, which conveys to any one skilled in the art of weaving silk badges a clear understanding of the same, and is sufficient to enable such person to use my invention.

The leading feature of my design consists in a portrait of Alexander Hamilton and a representation of the Passaic falls, at Paterson, New Jersey.

The badge is intended as a souvenir of the

centennial celebration of the founding of the city of Paterson, New Jersey, by Alexander ²⁰ Hamilton.

Besides the portrait and representation referred to, the badge will contain at the top thereof the representation of an eagle in flight holding in its talons an American flag and a ²⁵ scroll above the representation of the Passaic falls.

What I claim as my invention, and desire to secure by Letters Patent, is—

The design for a badge, substantially as described and shown.

JOHN BEST.
